UNITED STATES PATENT OFFICE

99,675

DESIGN FOR A PROJECTOR CASING

Edwin C. Fritts, Rochester, and Walter D. Teague, New York, N. Y., assignors to Eastman Kodak Company, Rochester, N. Y., a corporation of New York

Application April 4, 1936, Serial No. 61,955

Term of patent 14 years

To all whom it may concern:

Be it known that we, Edwin C. Fritts and Walter D. Teague, citizens of the United States, residing at Rochester, New York, in the county of Monroe and State of New York, and at New York city, in the county of New York and State of New York, respectively, have invented a new, original, and ornamental Design for a Projector Casing, of which the following is a specification, reference being had to the accompanying drawing forming a part thereof:

In the drawing:

Fig. 1 is a perspective view of a projector casing showing the front and one side of the casing and illustrating our new design.

Fig. 2 is a perspective view of the projector casing shown in Fig. 1, but illustrating the back and the opposite side of the casing from that shown in Fig. 1.

We claim:

The ornamental design for a projector casing as shown.

Signed at Rochester, New York, this 31st day of March, 1936.

EDWIN C. FRITTS.
WALTER D. TEAGUE.
